CONTROL FOR LIQUID CONTAINERS

Richard B. Esselman, Manhattan Beach, Calif., assignor to Farr Company, Los Angeles, Calif., a corporation of California

Application March 5, 1951, Serial No. 213,986

16 Claims. (Cl. 137—589)

This invention relates to a control for a liquid container and it is a general object of the invention to provide a simple, effective, dependable structure including, a valve and an operating mechanism therefor forming a unit readily detachable from the container and having operating parts maintained above the level of liquid in the container.

The mechanism, as provided by the present invention, is applicable to a liquid container and may, for example, be applied to an open topped tank or like vessel. The mechanism of the invention provides a drain valve to control flow through a drain opening provided in the bottom of the tank. In construction the drain valve involves a body applied to the bottom of the carrier, the body being a bowl-like element located below the carrier and depending therefrom. A head is engaged with the body and is supported on an upwardly facing shoulder in the rim portion of the body and is sealed therewith by a washer. Two fluid passages are provided through the head, one being an outlet passage communicating with the bottom of the tank and the other an overflow opening. A suitable means releasably secures the head to the body and the valve proper is a disc-shaped member in the body cooperating with a seat provided on the head and surrounding the outlet opening. A stem carries the valve and is guided by a projection provided on a boss that projects up from the head. A standard projects up from the head and is carried by the boss, the standard being tubular and being in communication with the overflow opening of the head. An overflow opening is provided in the standard at the point where it is desired to maintain the level in the tank. Operating means for the stem is provided at the upper end of the standard and involves a housing fixed on the standard and also held by a supplemental support that is located on the tank. A shiftable element is provided in the housing and has a normal up position and an actuated down position. A coupling is provided between the shiftable element and the stem. The coupling involves a stop on the stem, a yoke-type link slidable on the stem and attached to the shiftable element, and a spring acting under compression between the stop and the link. In one form of the invention the shiftable element is a crank carried on a shaft operated by a lever exposed so that it can be manually engaged. It is contemplated that the shiftable element may be a core to be operated by a coil which is under control of a switch operated by a suitable timing device. In the latter form of the invention I have shown a switch in the housing operated by a lever preferably provided with a float located in the tank.

It is a general object of this invention to provide a mechanism of the general character referred to characterized by a unitary assembly normally releasably held in operating position and such that it can be easily and quickly detached for purpose of removal when it is desired to effect replacement, repair, or cleaning.

Another object of the invention is to provide a mechanism of the general character referred to in which the operating means or mechanism located above the level of

2

the liquid in the tank is supported primarily by the standard, which projects up from the valve mechanism located at and carried by the bottom of the tank.

It is another object of the invention to provide a mechanism of the general character referred to having a simple, effective, dependable operating means including a coupling engaged with the stem of the valve providing for overtravel of the operating means after the valve has been closed.

Further, it is an object of the invention to provide a practical and compact structure including a valve, operating means for the valve, and a float control which elements form a simple unitary structure.

The various objects and features of my invention will be fully understood from the following detailed description of typical preferred forms and applications of the invention, throughout which description reference is made to the accompanying drawings, in which:

Fig. 1 is a sectional view of a portion of a tank showing the mechanism of the invention applied thereto. Fig. 2 is a sectional view taken substantially as indicated by line 2—2 on Fig. 1. Fig. 3 is a view taken as indicated by line 3—3 on Fig. 1. Fig. 4 is an enlarged detailed sectional view taken as indicated by line 4—4 on Fig. 2. Fig. 5 is a sectional view taken as indicated by line 5—5 on Fig. 4. Fig. 6 is an enlarged detailed sectional view taken as indicated by line 6—6 on Fig. 1. Fig. 7 is a view similar to Fig. 1, showing another form of the invention. Fig. 8 is an enlarged detailed sectional view taken substantially as indicated by line 8—8 on Fig. 7. Fig. 9 is an enlarged plan section taken as indicated by line 9—9 on Fig. 7, and Fig. 10 is a diagrammatic view illustrating the electrical circuit involved in the mechanism shown in Figs. 7, 8 and 9.

Referring first to the form of the invention illustrated in Figs. 1 to 6, inclusive, the mechanism of the present invention is applied to a suitable liquid carrier or vessel such as a tank A, and it is such as to control flow of fluid from the tank through an opening 10 in the bottom 11 thereof. The particular tank illustrated in the drawings is of simple or conventional form and has a side wall 12 projecting up from the edge of the bottom to a point somewhat above the level of liquid L to be normally maintained in the tank.

The mechanism provided by the present invention involves, generally, a drain valve B located at or carried by the bottom of the tank A and serving to control flow or passage of fluid through the opening 10. A standard C is carried by and projects upwardly from the drain valve B and supports an operating means D which is located at the upper end of the standard and at a point above the level of the liquid L.

The drain valve B, as provided by the present invention, involves, generally, a body 20 having a bowl portion 21 and a rim portion 22. The valve B further includes a head 23 carried by the body 20 and releasable means 24 normally securing the head on or in connection with the body. The head of the drain valve is characterized by a drain opening 30 that provides communication between the interior of the tank and the bowl 21 of the head, and by an overflow opening 31 that provides communication between the standard C and the bowl of the body, as hereinafter described. In the particular case illustrated the bowl 21 of the valve body 20 has a lateral outlet extension 33 from which fluid drained from the tank can be discharged or delivered to a drain line 34, as shown in Fig. 1 of the drawings.

In the particular case illustrated the body 20 of the drain valve has a mounting flange 35 at the upper periphery of the rim portion 22 and the flange 35 is secured to the bottom 11 of the tank, as by welding or the like. In the particular arrangement illustrated the

flange 35 is applied to the bottom or lower side of the bottom 11 and as a result the bowl portion of the body depends below the bottom 11 of the tank. Through this arrangement all of the fluid or liquid carried in the tank can be drained into the body of the valve for discharge therefrom.

The head 23 of the valve is preferably a unit, say, for example, a casting, and it is supported in the rim portion 22 of the body 20. In the preferred arrangement an upwardly facing shoulder 38 is provided in the rim portion of the body and a suitable seal or washer 39 is provided between the peripheral portion of the head 23 and the shoulder 38, as shown in the drawings.

The releasable means 24 connecting the head 23 and body 20 is shown as involving screw fasteners. In the case illustrated there are two screw fasteners at diametrically opposite points and each involves a bolt 40 engaged with a bifurcated lug 41 projecting upwardly and outwardly from the head and is threaded into an opening 42 provided in the rim portion 22 of the body. The bifurcated lugs 41 project up from the head 23 occurring within the rim portion of the body and they project laterally to overlie the portions of the rim in which the openings 42 occur. The bolts 40 are vertically disposed and their heads 44 are at their upper ends so that they are readily accessible.

The valve proper 45, is a disc-like element located in the bowl portion 21 of the body 20 and it is normally engaged with a seat 46 projecting downwardly from the head 23 and surrounding the outlet opening 30. The valve 45 which may be of any suitable material that will effectively seal with the seat 46 is carried by a stem 48 and it is preferred that the valve be adjustably secured on the stem. In the case illustrated spaced nuts 49 are threaded on the lower end portion of the stem 48 and washer-like plates 50 are carried on the stem at opposite sides of the valve where they are retained by the nuts. The stem 48 projects vertically from the valve to a point above the level of liquid L in the tank and its lower end portion is slidably supported by a guide 51 shown projecting from a boss 52 that projects upwardly from the head 23 at the drain opening 31.

The standard C is a tubular support carried by the boss 52 provided on head 23 to be in communication with the overflow opening 31 provided in the head 23. The standard projects upwardly to a point well above the level of liquid L and at the point where it is desired to maintain the level of liquid the standard is provided with an overflow opening 55. In practice a plurality of openings can be provided in the standard at or above this point to assure drainage through the standard rather than overflow of liquid from the tank. The lower end portion of the tubular standard is tight or fixed in the boss 52 and as a result the standard not only forms a support for the operating means D, as will be hereinafter described, but it also forms a drain or overflow duct that prevents flooding of the tank.

The operating means D is shown as involving a housing 60 supported by and fixed on the upper end of the standard C, a vertically shiftable element 61 and a connecting means 62 between the shiftable element 61 and the upper end portion of the valve stem 48. In the particular form of the invention under consideration the shiftable element 61 is a crank or, more specifically, it is a pin 63 provided on a crank arm 64, and the crank arm is provided on a shaft 65 rotatably carried by the housing 60 and adapted to be operated by a lever 66. The lever 66 is shown as a knob-like element on the exterior of the housing so that it is exposed for manual operation.

The means 62 connecting the shiftable element or pin 63 and the stem 48 is shown as involving a yoke-type link 70 pivotally carried on the crank pin 63 and slidably engaged with the stem 48. A stop 71 is provided on the upper end portion of the stem and a compression spring 72 is carried on the stem between the stop 71 and

the link at the point where the link is slidably engaged with the stem. The parts are arranged and proportioned so that when the crank pin 63 is in an up or normal position the link 70 has moved up somewhat beyond a position necessary to lift the stem so the valve 45 is seated and, consequently, the spring 72 is put under compression. A part 78 in the housing serves as a stop to limit the movement of the mechanism just described and stops it in a position somewhat over center so that it remains in the up position where the valve is closed until deliberately operated out of this position. When the crank is operated in a direction opposite to that indicated by the arrow in Fig. 5 it swings over center and can be moved to a down position where it is actuated, allowing the stem to lower and thus open the valve 45 allowing fluid to flow freely from the tank into the bowl of the drain valve.

In the particular case illustrated the housing 60 is in the form of a casting having a boss 79 that holds or 20 tightly receives the upper end of the standard C and the housing has a downwardly projecting skirt 80 that cooperates with a supplemental support 81. The support 81 is in the nature of a bracket fixed to the upper edge portion of the wall 12 of the tank and carries one or more 25 screw fasteners 82 received by downwardly opening notches 84 provided in the skirt 80. Through this construction, when the fastening means 24 is released and the fasteners 82 loosened the unit formed by the head 23, the valve 45, stem 48 and the operating means D can 30 be freely lifted away from or clear of the tank and the bracket 81. It is to be understood that the supplemental support formed by the bracket 81 can be used or not, as circumstances require, since the standard C is of such 35 construction and formation as to be an adequate support for the means D under most circumstances. It is to be observed that in accordance with the general construction and arrangement provided by the invention the standard projects not only above the level of liquid in the tank but actually above the upper edge 85 of the tank, and 40 as a result the operating means D is located well above and clear of liquid in the tank so that it is not affected or contaminated thereby.

In the form of invention illustrated in Figs. 7 to 10, inclusive, the drain valve B may be the same as that hereinabove described and the standard C may be carried by 45 the valve to project upwardly therefrom parallel with the valve stem 48, all as hereinabove set forth.

The operating means D' in this form of the invention involves a vertically shiftable element 61^a and a means 50 for operating the element 61^a. The element 61^a is connected with the stem 48 by a connecting means 62^a which 55 may be the same as that hereinabove described. The vertically shiftable element 61^a in this case is in the form of a core and the operating means therefor is a coil or winding 64^a to be energized under control of a switch S. The switch S, as shown in Fig. 10, is incorporated in a timer T which includes a suitable timing motor M. In practice, the timer may be such as to open the switch S at suitable intervals as circumstances require.

In the form of invention shown in Figs. 7 to 10, inclusive, I have provided a valve 100 for passing fluid into the tank A. Valve 100 may be any suitable electrically controlled valve and, as shown, it has an electrical actuator 101 attached thereto. Actuator 101 is under control of a switch S' controlled by a lever 66^a and in the case illustrated the lever carries a float 90 which operates in the tank so the actuator 101 is controlled by the liquid level in the tank. The switches S and S' may be of any suitable form or type. Switch S' in the case illustrated has a lever projecting therefrom that is protected 65 by a guard 91 of rubber or the like.

In the case illustrated a pin 61^b is carried on or may be considered as a part of the element 61^a and carries the yoke-like bracket 70 which is slidably engaged with the 70 valve stem 48. The bracket 70 engages the spring 72

which in turn engages the stop 71 provided on the upper end of the stem. The various parts of the operating means D' just described may be carried in a suitable housing 60^a carried on the upper end of the standard C and the housing may be further supported by the bracket 81 through a construction corresponding to that hereinabove described.

It will be apparent that with the mechanism just described the timer causes the switch S' to be opened at predetermined intervals so that the element 61^a is operated to open the drain opening 30. When the level of liquid in the tank drops below the predetermined level the switch S' is closed by action of float 90 causing the valve 100 to open and pass fluid into the tank. It will be apparent that with the mechanism that I have provided various actions can be obtained, as circumstances may require.

In the particular case illustrated a manually operated switch S'' is shown provided in the electric switch circuit so that the element 61^a can be operated under manual control whenever circumstances so require.

Having described only typical preferred forms and applications of my invention I do not wish to be limited or restricted to the specific details herein set forth, but wish to reserve to myself any variations or modifications that may appear to those skilled in the art and fall within the scope of the following claims.

Having described my invention, I claim:

1. A control for liquids including, a tank having an outlet opening at its bottom, a drain valve having a body adapted to be fixed to the exterior of the tank adjacent the opening and defining a fluid receiving chamber, a head within the opening engaged with the body separating the tank and the chamber and having a passage therethrough between the tank and chamber, coupling means releasably connecting the body and head, a valve member controlling flow through said passage, and a stem connected to and adapted to operate the valve member, a standard fixed to the head and projecting upwardly therefrom to the upper portion of the tank, operating means for the stem carried by the upper end portion of the standard and connected to the stem, a bracket adapted to be fixed to the tank, and fastening means releasably connecting the operating means to the bracket, the head, valve, stem, standard and said operating means forming a unit detachable from the body and bracket when the said coupling and fastening means are released.

2. In combination, a fluid receiving tank having a bottom, an outlet opening in the bottom, a drain valve having a body adapted to be fixed to the tank adjacent the said outlet opening and defining a fluid receiving chamber, a head engaged with the body to occur in the outlet opening and separating the interior of the tank and the chamber and having a passage therethrough between the interior of the tank and the chamber, coupling means releasably connecting the body and head, a valve member controlling flow through said passage, and a stem connected to and adapted to operate the valve member, a standard within the tank fixed to the head and projecting upwardly therefrom and terminating at the upper portion of the tank, and operating means for the stem carried by the upper end portion of the standard and connected to the stem, the head, valve, stem, standard and said operating means forming a unit detachable from the body when the coupling means is released.

3. In combination, a fluid receiving tank having a bottom, an outlet opening in the bottom, a drain valve having a body adapted to be fixed to the tank adjacent the said outlet opening and defining a fluid receiving chamber, a head engaged with the body to occur in the outlet opening and separating the tank and the chamber and having a passage therethrough between the interior of the tank and the chamber, coupling means releasably connecting the body and head, a valve member in the chamber controlling flow through said passage, and a stem connected

to and adapted to operate the valve member, a standard rigidly connected to the head and projecting upwardly therefrom to the upper portion of the tank, and operating means for the stem carried by the upper end portion of the standard and connected to the stem, the standard being tubular and located in the tank with its lower end in communication with the chamber and having an overflow opening at a predetermined elevation in the tank, the head, valve stem, standard and operating means forming a unit detachable from the body when the coupling means is released.

4. A control for liquids including, a tank having a bottom with an outlet opening, a drain valve having a body adapted to be fixed to the tank in communication with the opening and defining a fluid receiving chamber below the tank, a head engaged with the body separating the tank and the chamber and having a valve member in the chamber controlling flow through said passage, means releasably securing the head rigidly to the body, and a stem connected to the valve member, a rigid standard fixed to the head and projecting upwardly therefrom to the upper portion of the tank, and mechanical operating means for the stem connected thereto and carried by the upper end portion of the standard, the head, valve member, stem, standard and operating means forming a unit separable from the body when the first mentioned means is released.

5. A control for liquids including, a tank having a bottom with an outlet opening, a drain valve having a body adapted to be fixed to the tank adjacent the said opening and defining a fluid receiving chamber and having an upwardly facing shoulder, a head within said opening and engaged with the shoulder of the body and separating the tank and the chamber and having a passage therethrough between the tank and chamber, a valve member in the chamber controlling flow through said passage, screw fasteners operatively engageable from the interior of the tank and releasably retaining the head engaged with the body, and an operating stem connected to the valve member, a standard fixed to the head and projecting upwardly therefrom to occur within the tank and terminating at the upper portion of the tank, and operating means for the stem connected thereto and carried by the upper end portion of the standard, the head, valve member, standard, stem and operating means forming a unit separable from the body when the fasteners are released.

6. A control for liquids including, a tank having a bottom with an outlet opening therein, a drain valve having a body adapted to be fixed to the bottom side of the tank adjacent the said opening therein and defining a fluid receiving chamber, a head engaged with the body separating the interior of the tank and the chamber defined by the body and having a passage therethrough between the tank and chamber, coupling means releasably connecting the head to the body, a valve member in the chamber adapted to control flow through said passage, an operating stem connected to the valve member, and a guide on the head slidably carrying the stem, a standard fixed to the head and projecting upwardly therefrom to occur within the tank and project outward and beyond the upper portion of the tank, and operating means connected to the stem and carried by the upper end portion of the standard, the head, valve member, stem, standard and operating means forming a unit separable from the body when the first mentioned means is released.

7. A control for liquids including, a tank having a bottom and side walls, an outlet opening in the bottom, a drain valve having a body adapted to be fixed to the bottom of the tank adjacent the opening therein and defining a fluid receiving chamber below the tank, a head within the said opening and engaged with the body separating the tank and the chamber defined by the body and having a passage therethrough between the tank and chamber, a valve member in the chamber adapted to control flow through said passage, means releasably securing the head

to the body and operable from within the tank, and an operating stem connected to the valve member, a standard within the tank fixed to the head and projecting upwardly therefrom to extend beyond the upper portion of the side walls of the tank, and operating means connected to the stem and carried by the upper end portion of the standard, the standard being rigid and tubular with its lower end in communication with the chamber and having an overflow opening at a predetermined elevation in the tank, the head, valve member, stem, standard and operating means forming a unit separable from the body when the first mentioned means is released.

8. A control for liquids including, a tank having a bottom, an outlet opening in the bottom, a drain valve having a body adapted to be fixed to the tank adjacent the opening in the bottom and defining a fluid receiving chamber, a head occurring within said opening and engaged with the body separating the interior of the tank and the chamber and having a passage therethrough between the tank and chamber, a valve member adapted to control flow through said passage, and an operating stem connected to the valve member to project upwardly therefrom, a standard within the tank and fixed to the head to project upwardly therefrom adjacent to and parallel with the stem and terminating beyond the upper portion of the tank, and operating means connected to the stem and carried by the upper end portion of the standard to occur outside of the tank and including, a vertically shiftable element, coupling means connecting the stem and said element, and operating means for the said element including a manually rotatable shaft with a crank adapted to operate over center and connected to said element.

9. A control for liquids including, a tank having a bottom, an outlet opening in the bottom, a drain valve having a body adapted to be fixed to the exterior of the tank adjacent said opening and defining a fluid receiving chamber, a head engaged with the body separating the tank and the chamber defined by the body and having a passage therethrough between the tank and chamber, a valve member adapted to control flow through said passage, and an operating stem connected to the valve member and projecting upwardly therefrom through the passage in the head, a standard fixed to the head adjacent the passage therein and projecting upwardly therefrom to occur laterally offset from and parallel with the stem and terminating above the tank, operating means for the valve at the top of the tank connected to the stem and carried by the upper end portion of the standard and including, a vertically shiftable, spring cushioned link connecting the stem, and operating means for the said link including a rotatable crank on the standard pivotally connected to the link and adapted to be operated over center.

10. A control for liquids including, a tank having a bottom, an outlet opening in the bottom, a drain valve having a body adapted to be fixed to the exterior of the tank adjacent said opening and defining a fluid receiving chamber, a head within said opening and engaged with the body separating the tank and the chamber, a valve member in the chamber adapted to control flow through said passage, and an operating stem guided by the head and connected to the valve member, a standard rigid with the head and projecting upwardly therefrom to the upper portion of the tank, and operating means connected to the stem and carried by the upper end portion of the standard and including, a vertically shiftable element, a stop on the stem, a link connected to the element and slidably engaged with the stem, and a compression spring carried by the stem between the link and stop, the head, valve member, stem, standard and operating means forming a unit separable from the body when the first mentioned means is released.

11. A control for liquids including, a tank having a bottom, an outlet opening in the bottom, a drain valve having a body adapted to be fixed to the tank adjacent

the opening and defining a fluid receiving chamber, a head located in the opening in the tank and engaged with the body separating the tank and the chamber defined by the body and having a passage therethrough between the tank and chamber, coupling means releasably connecting the head to the body, a valve member in the body adapted to control flow through said passage, and an operating stem carried by the head and connected to the valve member, a standard fixed to the head and projecting upwardly therefrom to the upper portion of the tank, and operating means connected to the stem and carried by the upper end portion of the standard and including a housing mounted on the standard, a vertically shiftable element supported from and within the housing, and means connecting the stem and said element, the head, valve member, stem, standard and operating means forming a unit separable from the body when the first mentioned means is released.

12. A control for liquids including, a tank having an outlet opening, a drain valve having a body adapted to be fixed to the exterior of the tank adjacent the said opening and defining a fluid receiving chamber, a head within the opening and engaged with the body separating the tank and the chamber defined by the body and having a passage therethrough between the tank and chamber, coupling means releasably connecting the head to the body, a valve member adapted to control flow through said passage, and an operating stem connected to the valve member to project upwardly therefrom and through the passage in the head, a standard fixed to the head and projecting upwardly therefrom to the upper portion of the tank, and operating means connected to the stem and carried by the upper end portion of the standard and including, a housing on the standard, a vertically shiftable element supported within the housing, means connecting the stem and said element, and a supplemental support for the housing including a bracket adapted to be fixed to the tank and engaged by the housing and coupling means releasably connecting the housing to the bracket, the head, valve, stem, standard and said operating means forming a unit detachable from the body when the coupling means are released.

13. A control for liquids including, a tank having an outlet opening at its bottom, a drain valve having a body adapted to be fixed to the tank adjacent the opening and defining a fluid receiving chamber, a head within the opening engaged with the body separating the tank and the chamber and having a passage therethrough between the tank and chamber, coupling means releasably connecting the head to the body, a valve member adapted to control flow through said passage, and an operating stem connected to the valve member, a standard fixed to the head and projecting upwardly therefrom to the upper portion of the tank, and operating means connected to the stem and carried by the upper end portion of the standard and including a housing on the standard, a vertically shiftable element supported within the housing, coupling means connecting the stem and said element, operating means adapted to shift the said element including an operating lever adapted to be manually operated, and a supplemental support for the housing including a bracket carried by the tank and engaged by the housing and a releasable fastener connecting the housing and the bracket, the head, valve, stem, standard and said operating means forming a unit detachable from the body when the coupling means are released.

14. A control for liquids including, a tank having an outlet opening at its bottom, a drain valve having a body adapted to be fixed to the exterior of the tank adjacent said opening and defining a fluid receiving chamber, a head within the opening engaged with the body separating the tank and the chamber defined by the body and having a flow passage therethrough between the tank and chamber, coupling means releasably connecting the head to the body, a valve member adapted to control flow through said passage, and an operating stem connected to the valve

member to project upwardly through the flow passage and into the tank a standard fixed to the head laterally offset from the passage and projecting upwardly therefrom and parallel with the stem to terminate at the upper portion of the tank, and operating means connected to the stem and carried by the upper end portion of the standard including, a rotatable crank, and a link connecting the crank and stem.

15. A control for liquids including, a tank having an outlet opening at its bottom, a drain valve having a body adapted to be fixed to the exterior of the tank adjacent said opening and defining a fluid receiving chamber, a head within the opening and engaged with the body separating the tank and chamber defined by the body and having a flow passage therethrough between the tank and the chamber, coupling means releasably connecting the head to the body, a valve member adapted to control flow through said passage, and an elongate vertically disposed operating stem in the tank extending through said passage and connected to the valve member, a standard fixed to the head laterally offset from the said passage and projecting upwardly therefrom to the upper portion of the tank, and operating means connected to the stem and carried by the upper end portion of the standard including, an elongate horizontally disposed rotatable shaft extending transverse the standard, a crank on one end of the shaft, a manually operable lever at the other end of the shaft, and a link connecting the said crank and the stem.

16. A control for liquids including, a tank having an outlet opening at its bottom, a drain valve having a body adapted to be fixed to the exterior of the tank adjacent
